Attorneys

UNITED STATES PATENT OFFICE.

CHARLES H. DAUM, OF RIVERSIDE, CALIFORNIA.

HEADLIGHT.

Application filed February 4, 1922. Serial No. 584,154.

To all whom it may concern:

Be it known that I, CHARLES H. DAUM, a citizen of the United States, residing at Riverside, in the county of Riverside and 5 State of California, have invented a new and useful Headlight, of which the following is a specification.

This invention relates to headlights and is particularly directed to headlights adapted for use on automobiles and other vehicles.

An object of the invention is to provide a device of this character whereby the light from the lamp or source of light will be 15 effectively shielded from the eyes of pedestrians and other drivers and which will at the same time effectively light the road.

Another object is to provide a device whereby the light reaching the eyes of pedestrians or other drivers will be rendered nonglaring by the absorption of certain of 20 the light rays emanating from the light source.

A further object is to provide a device 25 by which the line of demarkation between the nonglaring light rays and those of maximum brightness is rendered more noticeable.

Various other objects and advantages will 30 be more fully apparent from the following description of the accompanying drawings which form a part of this disclosure and which illustrate a preferred form of embodiment of the invention.

35 Of the drawings:

Fig. 1 is a vertical central section through a headlight embodying the features of my invention.

Fig. 2 is a transverse section on line 2—2, 40 of Fig. 1.

Fig. 3 is a section similar to Fig. 1 showing a modified form of my invention, and

Fig. 4 is a transverse section on line 4—4, 45 of Fig. 3.

In practicing my invention I provide a translucent plate preferably of dark color which is disposed above the source of light and in a substantially horizontal position. In practice I prefer to provide two such 50 plates, one above the light and one below it.

In the structure shown in Figs. 1 and 2, 1 indicates the lamp housing supporting a suitable lamp socket for receiving the lamp bulb 3 and having a peripheral shoulder 4 against which the flange 5 of the reflector

6 seats, the housing at said shoulder having

one or more relatively spaced lugs 7 with which companion notches in the flange of the reflector mesh to prevent the reflector turning.

The flange 5 has a circular groove to receive a packing cord 8 and the front of the lamp is closed by a transparent glass disc 9, a rim member 10 holding the disc 9 against the cord 8 in the groove in the 65 flange 5 of the reflector and in turn holding the flange clamped against the shoulder 4 of the housing.

The reflector 6 which is preferably parabolic has a central opening through which 70 the lamp socket 2 extends, and above and below the lamp socket and bulb the reflector 6 has means for holding colored plates; for this purpose it may be formed to provide relatively spaced horizontal grooves 11 extending from one side edge to the other of the reflector.

Seated in said grooves are horizontally disposed translucent glass plates or partitions 12 of relatively dark color, as for instance dark blue or green, the plates being retained within their respective grooves by cement or other packing 13. These plates extend from the reflector surface outwardly to a plane substantially flush with the outer 85 edge of the reflector and form an intermediate chamber containing the source of light 3.

With this construction, the greater portion of the direct rays from the bulb 3 and all of the rays reflected from that portion of the reflector between the two partition plates 12 are projected directly forward with their full power through the transparent front glass 9, while all the light that 90 passes through the colored partitions 12 is subjected to an absorption of all the rays excepting those of a color corresponding to the color of the glass of which the partitions are formed. It will therefore be 100 understood that all the light projected from the lamp by refraction passing through the said partitions, and directly out, and all light passing through said partitions and then reflected by those portions of the reflector 105 above the upper partition or below the lower partition, will be rendered nonglaring by absorption.

Further by reason of the straight horizontal front edges of the partitions the line 110 of demarkation between such colored non-glaring light rays and the white light of

greater intensity will be rendered more noticeable.

The form of device shown in Figs. 3 and 4 constitutes a removable reflector which 5 is adapted for insertion into headlights of standard construction without alteration of such headlights, and comprises a reflector unit 15 formed of glass and conforming approximately to the general circular 10 concave shape of the ordinary headlight reflector 16 with which the headlight is initially equipped. Such glass reflector unit 15 has a peripheral flange 17 which engages the packing cord 8 and has the horizontal 15 translucent colored partitions 12^a formed integral therewith, said partitions being of the same shape and having the same function as the previously described partitions 12. The glass disc 9 engages a packing ring 18 placed 20 between it and the flange 17 of the reflector 15 and the several parts are retained in place by the rim member 10.

The surface 19 between the two partitions 12^a is silvered or otherwise rendered highly 25 reflective and the surfaces 20 outwardly from said partitions may or may not be silvered, as desired.

While I have illustrated and described my 30 preferred forms of embodiment of the invention, it is to be understood that the invention is not to be limited in this regard as it is susceptible of embodiment in various 35 other forms all coming within the scope of the following claims.

35 I claim:

1. In a headlight, the combination of a

reflector, a source of light centrally disposed in front of the reflector, the reflector having horizontal grooves on opposite sides of said light source, and translucent glass plates of 40 relatively dark color positioned in the grooves.

2. In a headlight, the combination of a reflector, a source of light disposed centrally in front of the reflector, a pair of translucent plates of relatively dark color disposed 45 respectively on opposite sides of the light and extending outwardly so that light rays passing upwardly and downwardly from the light pass through said plates, and 50 means on the reflector for holding the plates in position.

3. In a headlight, the combination of a reflector, a source of light disposed centrally in front of the reflector, said reflector having 55 a groove formed therein in a substantially horizontal plane above the position of the light, and a translucent plate of relatively dark color having its inner edge received in said groove so that the groove holds the 60 translucent plate in position, said plate extending outwardly above the light so that the light rays passing upwardly from the light pass through said plate and are reflected outwardly thereafter by said reflector. 65

Signed at Riverside, Calif., this 25 day of January, 1922.

CHARLES H. DAUM.
